LOG TYPE BUILDING STRUCTURE

Fred Williams, Three Lakes, Wis.

Application October 13, 1939, Serial No. 299,228

7 Claims. (Cl. 20—4)

My invention relates to improvements in log type building structures, with particular reference to structures of that type in which half logs or slabs, having their natural contours exposed, are individually supported by a suitable frame.

A primary object of my invention is to provide a substantially air-tight, moisture and vermin-proof structure of the half log or slab type, which can be inexpensively produced, and which is less subject to decay than structures of said type as heretofore made.

Further objects are to preserve the natural log contours of the exposed surfaces—to provide adequate heat insulation—to provide improved corner, door and window frame joints, and to allow each log to shrink without imposing strains or opening joints in a manner to allow entry of wind, water or vermin.

More specifically, it is my object to provide the half logs or slabs with flexible, or flexibly yielding, metallic connections along the opposing surfaces, said connections being substantially concealed and having a water shedding pitch which increases as the logs tend to shrink and separate. Also, to provide metal strips of angle iron shape, having flanges of unequal width and adapted by reversal, to meet the requirements of logs of differing size or having flat top and bottom surfaces which vary in width in different portions of the wall.

In the drawings:

Figure 1 is a perspective view of the corner portion of a partially completed log structure, as viewed from the exterior along a line bisecting the angle.

Figure 2 is a view of the same taken from a different angle and showing one wall with the inner side exposed and with battening strips, insulation and portions of the inner log wall members partially broken away.

Figure 3 is a detail sectional view of one of the half logs or slabs and its associated connecting metal strip.

Figure 4 is a similar view, showing a smaller log member having a correspondingly narrow top surface and with the metal strip reversed to apply its narrower flange to the top side of said member.

Figure 5 is a sectional view showing two superposed logs as they appear after separation by shrinkage, the horizontal flange of the connecting strip being lifted from the lower log member adjacent the angle, said angle having become obtuse and the horizontal flange having a water

shedding pitch in the direction of its outer margin.

Figure 6 is a plan view of a fragment of an inner angle corner.

Figure 7 is a detail view of a door frame or window joint, showing how the log members are prepared to receive the facing strips or trim.

Figures 8, 9, 10 and 11 are sectional views, showing successive portions of a single tree trunk as they are respectively prepared for use as structural elements of my improved log type building structure.

Like parts are identified by the same reference characters throughout the several views.

15 The building frame may be constructed in any ordinary manner, 4 x 4 studs being preferably used. The top portions of the tree trunks may be utilized as rafters. The lower portions may be sawed longitudinally to provide slabs of the required dimensions, the edges being then sawed to provide top and bottom surfaces of the desired width. If the logs are of large diameter, the portions between the slabs may be utilized as boards or material from which boards may be cut. The intermediate portions of the tree trunk may be sawed longitudinally along the center line to produce half logs and the edges trimmed to provide flat surfaces similar to those at the top and bottom margins of the slabs.

20 20 The half logs and slabs constitute the wall members of my improved building structure which serve as its outer and, if desired, the inner face of the wall.

25 In accordance with common practice, the lower course of outer wall members is first laid, leveled and nailed to the studs. For this course, the larger log members will be selected from those available if the preferred method is followed.

After laying the first course of log members 10 and securing them to the studs 11, metallic angle strips will be applied, each having portions 12 resting on the flat top surfaces of the first course members, and flanges 13 projecting upwardly in contact with the studs. The portions 12 will

40 40 then be nailed to the first course log members along the outer margins of these portions, and the next course of log members superposed and nailed to the studs. From the inner side, the vertical flanges 13 will then be nailed to the 45 45 superposed log members along their major, or vertically disposed flat surfaces.

50 Succeeding courses will be laid in the same manner, and each successive course may comprise logs which are smaller in the vertical dimension, if the available logs require such selec-

tion. When the wall is completed, each log member will be individually supported by the studs or frame members of the building and each will have its major or inner flat face secured to the vertical flange or flanges of the associated metal angle strip as to all log members above the bottom course. Also, each log member will have its flat top face secured to the portions 12 of the associated angle strip or connecting member.

When the logs shrink, they do not settle together, their positions being maintained by the frame, but the connecting members are lifted at their angles by the vertical flanges connected with the upper associated log member, the portions being inclined outwardly and downwardly to the line of their connection with the top face of the log member below.

When laying upper courses of smaller logs, or log members having top and bottom flat surfaces of less width than those of the larger lower members and the width of the portions 12 of the connecting members, I preferably reverse the connecting members as indicated in Figure 4, to bring their flanges 13 in contact with the top flat face of the log member below, and nail the wider portions 12 to the major flat or vertical face of the superposed log. I am thus enabled to avoid material exposure of metal edges at the outer face of the wall even though the smaller log members may have narrower top and bottom faces than those of the larger members.

The flat top surface 15 of each log member may have an outer margin chiseled or planed off to an inclined plane to provide a nailing face for the horizontal flange of the connecting member as indicated at 16 in Figure 4, or the entire surface 15 may have a downward and outward inclination. The connecting members may be composed of galvanized sheet metal or other non-corrosive strips, and, if desired, instead of inclining the top surface of any portion of the log member, the outer margin of the connecting strip may be slightly depressed by applying a roller or any other suitable tool just outside of the nailing line. Such a relatively inclined margin is indicated at 17 in Figure 3. The connecting strip being of light gage and flexible, it may easily be made to so incline, either before or after applying and nailing the strip in position.

At outer corners, alternate logs in one of the mating courses are extended as indicated at 19 and in the other mating course, the intermediate logs are so extended as indicated at 20.

The logs which do not so extend are butted against the major flat or vertical surface of the companion log in the mating course.

At window and door openings, studs are set to receive the ends of the logs. The logs are cut away to provide flat end portions 22 to receive the facing strips of the window and door openings.

Also, at window and door openings, I preferably bevel the log member at 23, between the rounded natural face and the portion 22. The rounded natural face is not only peeled by ordinary bark removal, but is preferably re-peeled by removal of sap wood in areas of irregular dimensions, thereby enhancing the appearance of the structure.

At inner corners or re-entrant angles, the mating log members may all be beveled to produce mitered joints (Figure 6). Preferably at all corners, one or both flanges of the connecting strip are extended as a separate flap 25 or 26 (Figure

1), to be lapped upon the flange of the mating strip or applied to an associated face of a mating log member. The metal is thin and has little or no tendency to separate superposed logs.

5 The inner face of my improved wall may be constructed in any suitable manner. I may use log members similar to those described for the outer wall or face, but ordinarily, no connecting strip will be required. While laying up the log
10 members of the inner wall, I preferably apply battening strips 30 (Figure 2), to the vertical flanges of the connecting strips used in the outer face, and then fill in the space between studs with heat insulating material 31. The purpose
15 of the battening strips also used between studs is to avoid all tendency of the metal strips to promote condensation by having metal surfaces in contact with the insulation, as might be the case if moist air were permitted to penetrate the
20 inner wall face.

While I have described my invention as applied to a structure in which the log members extend horizontally, I do not limit its scope to exclude similar structures in which the log members are vertically disposed. In either case the metal strips are effective to exclude wind, water and vermin. Also, I do not limit the scope of my claims to structures in which the metal rests directly upon the log members as distinguished from structures in which a padding of oakum or similar yielding material is interposed.

In Figure 8 I have illustrated the manner in which I utilize substantially entire tree trunks. The butt end or lower portions have slabs 10 cut away to be used in the lower portions of my improved wall. The central portions are sawed into boards 35 which may be utilized as sheathing or roof boards. After cutting one or more boards from one or more lengths of the log, one or more of the next lengths may be longitudinally divided to form the top members of the wall. Beyond these the top portions of the log may be cut into rafters 37.

I claim:

45 1. In a building structure, the combination with a supporting frame, of exposed log-like members secured to the outer faces of the frame, with their natural log contours exposed, interposed impervious strips of flexible material, each having its outer margin secured to one edge of one of the log members and having an inner portion secured to the inner face of the opposing log member, each of said strips constituting an extensible seal between the two log members to which it is attached, an inner wall carried by said frame, and a filling of insulating material between said walls protected from the elements by said strips notwithstanding shrinkage and separation of said log members.

60 2. A building structure as set forth in claim 1, in which the sealing strips are formed of metal and their inner faces covered by non-metallic battening strips to protect the insulation from condensation.

65 3. In a building structure of the described type, an outer wall comprising the combination of a set of superposed slab-like log members having outer faces substantially of natural log contours with the bark and portions of the sapwood removed, flexible metal strips interposed between the opposing edge margins of the wall members and marginally secured to the top faces of the respective members, each metal strip having an inner portion secured to the inner face of the
70 associated superposed member, said metal strips

being substantially wholly concealed by the wall members and adapted to maintain a wind, water and vermin-tight connection between them notwithstanding shrinkage of the wall members, and sealing means at the building corners connecting said strips with like strips in mating walls.

4. In a log type building structure, the combination with a supporting frame, of an outer wall composed of horizontally disposed log-like members having flat top, bottom and inner surfaces, and outer surfaces of natural log contour, each of said members being connected with the frame for support independently of the other members, concealed sealing strips, each capping the top portion of one member and having its front margin secured thereto and its rear margin up-turned and secured to the inner face of the superposed member, whereby the rear margin of the capping portion of the strip is adapted to be progressively lifted upon separation of the logs during shrinkage to develop a water shedding pitch of the capping portion.

5. A building structure as set forth in claim 4, in which the capping portions of the connecting strips are extended at the corners and the extended portions lapped upon each other at the meeting ends of the capping strips pertaining to the respective walls.

6. In a log type building structure, the combination with a supporting frame, of an outer wall composed of a series of horizontally disposed saw trimmed wall members of slab-like contour, the outer surfaces of which have substantially natural log curvatures, a series of metal strips

5 having longitudinally extending portions of different widths substantially at right angles to each other, some of said strips having their narrow portions capping the top face of a wall member and marginally secured thereto adjacent the outer surface of the wall member, and the other strips having their wider portions capping the tops of larger log members and similarly secured thereto, each of said strips having vertical portions extended along the inner faces of associated superposed log members and secured thereto, the intermediate capping portions of all the strips being free for flexion increasingly to a water shedding position when shrinkage of 10 15 the wall members causes them to separate from each other.

7. A building structure, having in combination an exposed wall face, comprising a series of superposed independently supported slab-like log members, having their natural log contours exposed and their upper and lower edges saw-trimmed to provide flat surfaces opposed to those of the adjacent log members in the series, elongated flexible metal sealing caps each covering the upper saw-trimmed edge of one log member and provided with an upturned flange along its rear margin secured to the rear face of the superposed log member along a line above the cap, each cap being also secured to the capped saw-trimmed edge along a line corresponding generally with the front margin of said edge, and the intermediate portions of the cap being adapted to yield vertically to maintain the seal when the log members separate by shrinkage.

FRED WILLIAMS.
